UNITED STATES PATENT OFFICE.

MATTHEW HENRY WHITTAKER, OF SALFORD, AND CHARLES HENRY WEST, OF LEEDS, ENGLAND, ASSIGNORS TO THE MERGENTHALER LINOTYPE COMPANY, OF NEW YORK, N. Y.

MOLD OF LINOTYPE-MACHINES

SPECIFICATION forming part of Letters Patent No. 672,199, dated April 16, 1901.

Application filed January 18, 1901. Serial No. 43,799. (No model.)

To all whom it may concern:

Be it known that we, MATTHEW HENRY WHITTAKER, of Salford, in the county of Lancaster, and CHARLES HENRY WEST, of Leeds, 5 in the county of York, England, have invented certain new and useful Improvements in the Molds of Linotype-Machines; and we do hereby declare the following to be a full, clear, and exact description of the invention, such 10 as will enable others skilled in the art to which it appertains to make and use the same.

The present invention relates to improvements in the molds of linotype-machines.

A linotype is a bar of type-metal as long as 15 a column or a page of printed matter is wide and having along one of its edges the type-faces duly composed, spaced, and justified into words for printing a line. The mold for the type-faces is constituted by a line of formative cavities or matrices proper in a line of 20 matrix plates or bars, and that for the body of the linotype by a slot of the proper size in a suitable block of metal. When the two molds just described are made to register 25 with each other in the proper respective positions and the back of the body-mold is closed, melted type-metal is injected into the compound mold, a linotype being thereby cast. The sides and ends of the slot above mentioned 30 are parallel with each other, respectively, and all its angles are right angles, the linotype body having necessarily a corresponding form. Consequently the linotypes are not adapted when they are set on their 35 feet on an impression-cylinder with the said feet parallel with the cylinder-axis to fit close up to each other over their sides, because the latter are parallel with each other and only linotypes having tapering sides can fit up to 40 each other in such a position. This incapacity of parallel linotypes for fitting close up to each other over their sides does not matter in printing-offices where curved stereoplates are used on the impression-cylinders; but it 45 makes itself felt whenever it is desired to print from linotypes held on the impression-cylinder or in a fudge-box parallel with the axis of the said cylinder.

The object of the present invention is to 50 adapt the linotype body-mold to cast taper-

ing ribs on one side of the said body, thereby producing what is practically a taper linotype, wider across the top than across its foot by as much as the radius of the impression-cylinder may render necessary to provide for 55 the taper linotypes fitting close up to each other over their sides when they stand in the above-described position on the impression-cylinder or in the fudge-box. Hitherto a parallel linotype has been ejected or pushed out 60 of the mold of a Mergenthaler linotype-machine, printing edge first, between a pair of parallel knives which have trimmed off both its sides, and now if tapered linotypes are wanted the knife on the ribbed side of the linotype is 65 moved out of working position. If, on the other hand, parallel linotypes are wanted, the said knife is left in working position. This capacity on the part of the knife on the ribbed side of being moved out of working position 70 and back again is no part of the present invention, being already well known.

When "leads"—that is, linotype-bodies only—are to be cast in a linotype-machine, the mold for printing-faces is replaced by a 75 plate which closes the respective side of the slot o. It is obvious that if the linotypes themselves must be tapered from printing edge to foot the leads must be tapered likewise. That being the case the present invention is as applicable to the casting of one as it is of the other.

Referring to the accompanying drawings, which are to be taken as part of this specification and read therewith, Figure 1 is a front 85 elevation of a mold-block of the well-known Mergenthaler linotype-machine made according to the present invention; Fig. 2, a plan of Fig. 1; Fig. 3, an inverted plan of the cap-plate of the said mold-block; Fig. 4, a perspective view of a linotype cast in the improved mold-block, and Fig. 5 a section of three such linotypes.

1 is the cap-plate; 2, the bottom plate; 3 3, the end liners, and 4 4 the screws holding the 95 four parts together in the respective positions, thereby establishing the slot o. The opposite faces of the plates 1 and 2 constitute the above sides of the slot, and the opposite faces of the liners 3 3 the above-mentioned ends 100

thereof. 5 5 are transverse grooves in the face of either the cap-plate 1 or that of the bottom plate 2. For convenience sake they are in the face of the cap-plate 1. Two only are 5 shown; but that number may be increased. No matter how many there are they are arranged symmetrically along the said face. These grooves are shown as semicircular in cross-section. They may be of any one that 10 will give the resulting ribs 6 6 a good bearing-surface against the adjacent linotypes 7; but they are all equally tapered from one end to the other, the depth at the deepest end being proportioned to the radius of the impression-cylinder on which the linotypes 7 cast in the slot 0 are to stand. The taper is gradual from the deepest end to practically nothing, or nearly to that, at the opposite end of the said grooves, as shown in Fig. 3, and is 15 so positioned across the face of the plate that the deepest end is next to that side of the slot 0 with which, front or rear, as the case may be, the mold for the printing-faces on the linotype 7 registers.

20 25 We are aware that the specification of Letters Patent No. 436,532, dated September 16, 1890, describes molds for linotype-machines having transverse grooves of equal depth throughout in one of their plates to cast ribs 30 on one side of each linotype, the function of such ribs being to increase the distance between the printing edges of the linotypes for the purpose of increasing the normal 35 distance between the printed lines. These grooves are hereinafter referred to as "leading-grooves;" but the essence of the present invention is not grooves as such nor the transverse position thereof. It is the tapered cross-section in a given direction of 40 not less than two grooves. Nevertheless, if linotypes ribbed to increase the normal distance between the printed lines and tapered also are required the grooves 5 are deepened 45 equally throughout their length accordingly, which will have the effect of making them a combination of the leading-grooves above mentioned, with the plate 1 or 2 on one side and with the tapered grooves 6 on the other, the leading portion of the compound groove 50 being of equal depth throughout, or the leading-grooves may be in one plate—say the plate 1—and the tapered grooves in the other.

55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800

such combinations being to prevent the taper of the grooves 5 contributing to the linotypes beginning to leave the slot 0 before the proper ejecting mechanism acts on them by engaging in notches 13 in the ribs 6. 65

We are aware that type-molds and linotype-molds have been provided with movable pins protruding into the mold and engaging the type or slug cast therein, such pins being combined with mechanical devices for retracting 70 them in order to permit the ejection of the type or slug. In our structure the retaining device 11 is rounded and held to its place by a spring, the form and arrangement being such that when a pressure sufficient to eject 75 the slug is applied thereto the spheres or retaining devices will yield automatically and permit the escape of the slug. No mechanism is necessary for retracting the spheres, and it is their adaptability to operate automatically without the co-operation of controlling mechanism that forms the essence of our invention.

We claim—

1. A slotted linotype-mold having in one 85 side a plurality of transverse grooves increasing in depth toward the forward side.
2. A linotype-mold having therein a slot of uniform thickness from front to rear, and also having on one of its inner surfaces a plurality 90 of transverse grooves increasing in depth from one end to the other, whereby it is adapted to produce a slug having a body of substantially uniform thickness with tapered ribs thereon. 95
3. A linotype-mold having a slot there-through and tapered grooves in one wall of the slot, in combination with automatically-yielding members projecting into said grooves to prevent the premature movement of the 100 slug cast in the mold.
4. In a slotted linotype-mold, rounded, movable members 11 to retain the slug in position, in combination with springs to hold said projections normally in engagement with 105 the slug, whereby the retaining members 11 are adapted to yield automatically under the influence of the outgoing slug.
5. In a linotype-mold, a spring-supported device, adapted to yield when pressure is applied to the slug to effect its ejection from 110 the mold.

In witness whereof we have hereunto set our hands in the presence of two witnesses.

MATTHEW HENRY WHITTAKER.
CHARLES HENRY WEST.
